UNITED STATES PATENT OFFICE.

LYDELL L. WILSON, OF RANDOLPH, NEW YORK.

BED CONSTRUCTION FOR RAILROADS.

1,312,427.

Specification of Letters Patent.

Patented Aug. 5, 1919.

Application filed May 5, 1919. Serial No. 294,724.

To all whom it may concern:

Be it known that I, LYDELL L. WILSON, a citizen of the United States, residing at the village of Randolph, in the county of Cattaraugus and State of New York, have invented certain new and useful Improvements in Bed Construction for Railroads, of which the following, taken in connection with the accompanying drawings, is a specification.

10 The invention relates to railway beds and rail supports thereon; and the improvement consists in providing a reinforced concrete bed having a series of spaced pairs of cavities which have overhanging ends in order 15 to place a two-part interlocking rail cushion therein, said cushion locking beneath said overhanging ends in such a manner as to prevent movement of the same when held in place by the rail, yet permitting the removal 20 of the rail and cushion when desired, provision being made for the drainage of said cavities; and the invention consists in the novel features and combinations hereinafter set forth and claimed.

25 In the drawings, Figure 1 is a top plan view of a portion of the railway bed with the rails attached on the left portion of the same, and showing the empty cavities for the cushions in the right portion of said bed.

30 Fig. 2 is a sectional view at line 2—2 in Fig. 1 showing the construction and arrangement of the road bed with the rails attached thereon, the central portion being broken away. Fig. 3 is a perspective sectional view of a 35 rail and the railway bed, showing the preferred construction and arrangement of the same. Fig. 4 is a detail perspective view of one of the sections of the rail support or cushion. Fig. 5 is a diagram of the preferred 40 manner of insertion for the two-piece blocks; and Fig. 6 is a top plan view of the same after insertion. Fig. 7 is a top plan view of a modification showing a lengthwise joint instead of a crosswise joint between the two 45 rail block parts, and having the overhanging walls on the sides. Fig. 8 is a further modification showing a dovetailed shaped cavity for the overhanging end walls, and a two-piece rail block fitting the cavity.

50 Like characters of reference refer to corresponding parts in the several views.

In the drawings, the numeral 10 designates the concrete road bed which is made of sufficient width to support the railway track, and of sufficient thickness to support 55 the loads necessarily borne on said track. For a regular gage railway the bed 10 should be about eight feet wide and reinforced beneath each point of rail attachment by a crosswise rail or steel bar 11. 60

Two series of cavities 12 are provided spaced in alignment sidewise and lengthwise, which cavities are of sufficient size to receive the wood cushion 13 therein, which is made in two preferably equal parts, having the division joint 14 immediately beneath the center of the steel rail 15 when said rail is attached on said rail cushion 13. The lower edges are preferably chamfered each way as shown at 16, and the ends 17 of the cavities 12 are made overhanging, preferably being formed in a curve or semi-circle, and the ends 18 of the cushion blocks 13 are rounded to fit within the curved ends 17 of the cavities 12 so that by means of the chamfered opening 16 across the lower edges of the central joint 14, the two cushion blocks 13 may be pressed or turned down into the cavity 12 by pressing downward on their central portions or joint 14 thereby bracing 75 against each other and the ends 17. The rail 15 is attached immediately over said joint 14 so that the two cushion blocks are held firmly in place. The cushion blocks 13 are made to fit closely within the cavities 12 80 thereby rendering said cushion blocks exceedingly rigid when pressed into binding engagement within the cavities 12. A reinforcing rod 19 is provided at each end of the cushion blocks 13 and cavity 12 which 85 extends lengthwise of the bed thereby reinforcing the concrete and strengthening the overhanging edge 20 at each end of the double cushion block 13.

In order to drain the cavities 12, drainage holes or tubes 21 are provided which extend from the cavities 12 to the bottom of the bed 10. The holes 21 are preferably made by placing a soft wood rod in the fluid cement when the concrete bed 10 is constructed, which soft wood rod soon decays leaving the hole 21 in the hardened cement. 95 100

It will be appreciated that immediately following the construction of the bed and placing the wood cushions 13, said cushions would so closely fit the cavities 12 as to prevent water from seeping into the cavities. By constant use, however, the cushions are worn away so as to permit the water to enter the cavities 12. It will then have freedom of exit therefrom. Leading grooves 22 may be made in the bottom of the cavities 12 to the hole 21 to conduct the water.

The rail 15 is preferably attached as stated over the central joint 14 of the blocks 13 by means of a corrugated plate 23 which has a smooth central portion for the base of the rail 15 and holes therethrough for the attaching bolts 24 at each side. Holes 25 are provided in the cushion blocks 13 for the attaching bolts 24, said holes or openings 25 having an enlargement at their lower end to receive the heads of the bolts 24 so that said heads can be drawn up into the enlarged lower end of the hole 25 and away from the concrete bed 10, to thereby insulate the rails 15 from the damp concrete bed 10 as shown in my former Letters Patent No. 1,293,598.

The rails 15 are held in attachment upon the bed plate 23 by the bolts 24 which pass through similarly corrugated holding plates 26, the opposite inner edges of the plates 26 extending on to the lower flange of the rail 15, locking latches 27 being provided for the nut 28 of the bolt 24.

It is now obvious that the rails 15 may be quickly attached to the cushion blocks 13 and are easily removable therefrom by the simple attachment with the bolts 24 and plates 23 and 26. When it is desired to remove the rail 25, the nuts 28 are removed from the bolts 24, thereby permitting the removal of the holding plates 26 and the rail 15, after which the bed plate 23 may be removed and the cushion blocks 13 drawn upward at their central portion, the semi-circular ends 18 in the similarly curved ends of the cavities 12 permitting the easy withdrawal of the cushion blocks 13 for renewal or repair, or for the repair of the road bed.

The drainage holes 21 are provided in the lowest portion of the cavities 12; for example, in rounding a curve it will be appreciated that the concrete bed 10 will be at an incline with the cavities 12 at the same angle of inclination and the holes 21 will, of course, be placed at the lower end of the cavities so as to give the best drainage. The central joint 14 as stated is preferably made crosswise of the center of the cavity 12, the blocks 13 being made so close a fit and the ends 18 made in semi-circular form, said blocks 13 hingingly press down into the wedging horizontal position from the upwardly inclined position as shown in the

diagram in Fig. 5, in which the blocks 13 65 are at the upward angle and the dotted horizontal line shows the strong wedging contact into which said blocks are forced by heavy downward pressure, the beveled or chamfered lower corners being so adapted to one another as to wedgingly force the blocks 13 into as strong holding contact against one another as possible.

The modification shown in Fig. 7 shows blocks 29 which extend lengthwise of the cavity 30, and have the curved or overhanging walls on the sides of cavity 12 instead of at the ends as shown at 17. It is apparent that a sectional block could thus be inserted by having chamfered edges and serve a good purpose, but would not be as firm and strong as where the joint 14 comes under the plate 23 and rail 15, which thereby holds the blocks 29 at the joint 14 firmly in position so that they cannot creep and gives strong holding anchorage for the bolts 24 through each of the blocks 13. Any form of sectional rail block demands that opposite cavity walls be overhanging so far as the block is concerned and that the other opposite sides be straight so that the sectional parts of the block may be turned down into holding engagement in the cavity.

The modification shown in Fig. 8 shows the cavity 31 with straight overhanging end walls giving a dovetailed shape to the cavity, that is, said cavity enlarges inwardly as to its end walls. The rail block is made in two parts 32 and 33, the part 32 being dovetailed shape, while the part 33 has the same angle for each of its end walls so that it slips freely into the remaining opening after the block 32 is inserted and the plate 23 and rail 15 with their holding engagements lock the two parts 32 and 33 firmly in position. This modified form serves a good purpose for certain tracks, the dovetailed shape holding the sectional rail block firmly in position.

I claim as new:

1. A railroad bed comprising a concrete bed having spaced openings therein, a two-piece rail block shaped to be received in each of said openings, overhanging walls in each of said openings to hold the outer ends of said two-piece rail block thereunder, the central lower edges of said blocks chamfered in opposite directions to permit the wedging insertion thereof in said openings.

2. A railroad bed comprising a concrete bed having two series of spaced openings therein alined in pairs one series to each rail, oppositely curved overhanging end walls in said openings, and sectional rail blocks having similarly shaped ends to wedgingly fit in said openings under said overhanging ends.

3. A railroad bed comprising a concrete

bed having two series of spaced cavities therein arranged in alignment lengthwise and crosswise, two of the opposite walls in each of said spaced cavities curved in semi-circular form, sectional rail blocks having their outer edges in semi-circular form to hinge and wedgily fit in said openings, the central lower edges of said blocks cham-

fered in opposite directions to permit the insertion thereof in said cavities.

In testimony whereof I have affixed my signature in the presence of two witnesses.

LYDELL L. WILSON.
